(57) **CLAIM**

The ornamental design for a pet bowl set as shown and described.

DESCRIPTION

FIG. 1 is a perspective view of a pet bowl set showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the pet bowl set showing the legs in a closed configuration;

FIG. 9 is an enlarged view of portion 9 shown in FIG. 1; FIG. 10 is an enlarged view of portion 10 shown in FIG. 1; and,

FIG. 11 is an enlarged view of portion 11 shown in FIG. 7. The broken lines in the drawings depict portions of the pet bowl set that form no part of the claimed design.

The dashed broken lines represent boundaries of the enlarged portions and form no part of the claimed design.

1 Claim, 11 Drawing Sheets
